UNITED STATES PATENT OFFICE.

GEORGE H. PAGE, OF WATERFORD, AND JESSE SCOTT BUTTON, OF SCHENECTADY, NEW YORK, ASSIGNORS TO COHOES ROLLING MILL CO., OF COHOES, NEW YORK, A CORPORATION OF NEW YORK.

ADJUSTABLE SKID FOR TUBE-MAKING APPARATUS.

SPECIFICATION forming part of Letters Patent No. 734,357, dated July 21, 1903.

Application filed September 22, 1902. Serial No. 124,281. (No model.)

To all whom it may concern:

Be it known that we, GEORGE H. PAGE, residing at Waterford, county of Saratoga, and JESSE SCOTT BUTTON, residing at Schenectady, county of Schenectady, State of New York, citizens of the United States, have invented certain new and useful Improvements in Adjustable Skids for Tube-Making Apparatus, of which the following is a specification.

10 The invention relates to such improvements; and it consists of the novel construction and combination of parts hereinafter described and subsequently claimed.

Reference may be had to the accompanying drawings, and the reference characters marked thereon, which form a part of this specification.

Similar characters refer to similar parts in the several figures.

20 Figure 1 of the drawings is a top plan view showing the draw-bench and delivery-trough of a tube-making apparatus provided with our improved adjustable skid mechanism. Fig. 2 is a cross-section of the same taken on the broken line 2 2 in Fig. 1 on a larger scale. Fig. 3 is a view, in side elevation, of the guide-trough for the free end of the skid. Fig. 4 is an end view of the same.

We have shown our invention in its application to a machine for making metal tubes wherein the tubes are formed from skelps, which are heated in the furnace and severally drawn through a shaping and welding bell upon a draw-bench, from which the tube is transferred to a delivery-trough, whence it is taken for further treatment. The delivery-trough is usually supported in a stationary position, while the draw-bench is made movable to adapt the same to be brought into line with the different skelps in the furnace. For convenience in transferring the tubes the delivery-trough may be located in a lower plane than the draw-bench.

Our invention is adapted for various uses, 45 being particularly adapted for use in connection with such a draw-bench and delivery-trough, the object of the invention in this connection being to permit the skids over which the tubes are transferred from the

draw-bench to the delivery-trough to automatically adjust and accommodate themselves to the different positions of the draw-bench due to its movement toward and from the delivery-trough.

Referring to the drawings, 1 is the delivery-trough, located at one side of and in a lower plane than the draw-bench 2, provided on its end adjacent to the furnace 3 with a shaping and welding bell 4. The draw-bench is pivoted at 5 upon a fixed support 6, whereby it is adapted to swing upon a vertical axis toward and from the delivery-trough, the swinging end of the bench being supported by a wheeled truck 7, adapted to travel upon the floor 8 or other way provided therefor, said draw-bench and delivery-trough being constructed and adapted to operate in the usual manner.

In carrying out our invention we connect with the movable draw-bench a plurality of 70 skids, each consisting of a rod 9, having at one end thereof a universal pivotal connection at 10 with such draw-bench and having its other end adapted to travel in and be supported by a guide-trough 11, projecting laterally from the delivery-trough 1 toward the draw-bench. The guide-trough may be secured to the delivery-trough in any known manner, as by providing the guide-trough with a flange 12, adapted to be bolted to the 80 side of the delivery-trough. The guide-trough opens beneath the delivery-trough, permitting the skid-rod 9 to play freely through the open end of the guide-trough beneath the delivery-trough, as the position 85 of said rod changes in accordance with the movement of the draw-bench. One wall 13 of the guide-trough is adapted to project from the delivery-trough in line with the top of the delivery-trough on the side adjacent to 90 the draw-bench. As the draw-bench is moved toward and from the delivery-trough it will be seen that the swinging ends of skid-rods 9 will be caused to travel along the respective guide-troughs 11, said rods assuming from 95 time to time different degrees of downward as well as lateral inclination. It will be seen, however, that in whatever position the draw-

bench may be located a tube may be rolled therefrom down the skid-rods 9 and along said rods until the tube engages the walls 13 of the respective guide-troughs, over which 5 walls it can be rolled into the delivery-trough.

Aside from permitting the draw-bench to be located on a higher plane than the delivery-trough, the construction shown and described permits an unlimited range of movement of the draw-bench toward and from the delivery-trough, the guide-trough opening beneath the delivery-trough, making it possible to project the skid-rod beneath and beyond the delivery-trough in bringing the 15 draw-bench into close proximity thereto.

What we claim as new, and desire to secure by Letters Patent, is—

1. In an apparatus of the class described, the combination with a pair of members one 20 movable toward and from the other; of a skid pivotally connected at one end with the movable member; and an open slideway or trough opening beneath the other member and projecting laterally therefrom toward the movable member, and adapted to receive and guide the other end of said skid, substantially as described.

2. In a tube-making apparatus, the combination with the delivery-trough, and the 30 draw-bench movable toward and from the same; of a skid pivotally connected at one end with said draw-bench; and a guide-trough

for the free end of said skid opening beneath said delivery-trough and projecting laterally from the top thereof toward the draw-bench, 35 substantially as described.

3. In a tube-making apparatus, the combination with a delivery-trough; and a draw-bench adapted to oscillate toward and from, and in a higher plane than, the delivery-trough; of a guide-trough opening at one end beneath the delivery-trough and projecting laterally from the top thereof toward the draw-bench; and a skid having a universal 40 pivotal connection at one end with the draw-bench, and its free end supported by said guide-trough and adapted to play through the open end thereof, substantially as described.

4. The combination with a pair of members one movable toward and from the other; of 50 a skid connected at one end with one of said members, and adapted to pass beneath the other member, when the members are brought into proximity to each other; and a guide adapted to support the free end of said skid 55 and direct the same beneath said other member.

In testimony whereof we have hereunto set our hands this 30th day of August, 1902.

GEO. H. PAGE.
JESSE SCOTT BUTTON.
